US0D1051828S

(12) **United States Design Patent** (10) **Patent No.:** **US D1,051,828 S**
(45) **Date of Patent:** **** Nov. 19, 2024**

(54) **POWER BANK JUMP STARTER**

(71) Applicant: **Vector Products, Inc.**, Boca Raton, FL (US)

(72) Inventor: **Ling To Shum**, Boca Raton, FL (US)

(73) Assignee: **Vector Products, Inc.**, Boca Raton, FL (US)

(**) Term: **15 Years**

(21) Appl. No.: **29/864,886**

(22) Filed: **Jun. 25, 2022**

(51) LOC (14) Cl. **13-02**

(52) U.S. Cl.

USPC **D13/107**

CLAIM

The ornamental design for power bank jump starter as shown and described.

DESCRIPTION

FIG. 1 is a top perspective view of an embodiment of the power bank jump starter.

FIG. 2 is a bottom perspective view of the embodiment of the power bank jump starter.

FIG. 3 is a top view of the embodiment of the power bank jump starter.

FIG. 4 is a bottom view of the embodiment of the power bank jump starter.

FIG. 5 is a front view of the embodiment of the power bank jump starter.

FIG. 6 is a back view of the embodiment of the power bank jump starter.

FIG. 7 is a right view of the embodiment of the power bank jump starter; and,

FIG. 8 is a left view of the embodiment of the power bank jump starter.

The broken lines shown in the drawings are for the purpose of illustrating portions of the power bank jump starter that form no part of the claimed design.

1 Claim, 6 Drawing Sheets
